UNITED STATES PATENT OFFICE.

RUBEN ANSON, OF TRUXTON, MISSOURI, ASSIGNOR OF ONE-HALF TO WILLIAM A. FEMMER, OF TRUXTON, MISSOURI.

DESIGN FOR A CHURCH CONTRIBUTION CHEST.

Application filed April 30, 1927. Serial No. 21,812. Term of patent 14 years.

To all whom it may concern:

Be it known that I, RUBEN ANSON, a citizen of the United States, and a resident of Truxton, in the county of Lincoln and State of Missouri, have invented a new, original, and ornamental Design for a Church Contribution Chest, of which the following is a specification, reference being had to the accompanying drawing, forming part thereof.

Figure 1 is a front elevation of a contribution chest showing my new design,

Figure 2 is a side elevation of a contribution chest, showing my new design, and

Figure 3 is a top plan view of a contribution chest showing my new design.

I claim:

The ornamental design for a church contribution chest, as shown.

RUBEN ANSON.
